UNITED STATES PATENT OFFICE.

CHARLES KAESTNER, OF CHICAGO, ILLINOIS.

ORE-CRUSHER.

SPECIFICATION forming part of Letters Patent No. 377,459, dated February 7, 1883.

Application filed May 24, 1884. Serial No. 132,673. (No model.)

To all whom it may concern:

Be it known that I, CHARLES KAESTNER, a citizen of the United States, residing at Chicago, in the county of Cook and State of Illinois, have invented certain new and useful Improvements in Ore-Crushers, of which the following is a specification, to wit:

This invention relates to an improvement in ore-crushers; and it consists in certain peculiarities of the construction and combinations of parts, substantially as will be hereinafter more fully described and claimed.

In order to enable others skilled in the art to which my invention appertains to make and use the same, I will now proceed to describe its construction and operation, referring to the accompanying drawings, in which—

Figure 1 is a top plan view, partly in section, of my improved crusher. Figs. 2 and 3 are reverse end elevations of the same. Fig. 4 is a longitudinal vertical section taken on the line $x-x$, Fig. 5; and Fig. 5 is a transverse section, taken on the line $y-y$, Fig. 4, of the machine as I prefer to construct it. Fig. 6 represents the manner of journaling the crushing-rolls.

A represents a base or main frame, on which is mounted in suitable boxes, $a-a$, the main driving-shaft A' , carrying two broad-faced rollers, A^2 , as shown in Fig. 4. Beside this shaft is mounted a second shaft, A^3 , also provided with rollers A^2 , and the two shafts are each provided with a belt-pulley, a' , connected by a belt, a^2 , by which motion is transmitted from one to the other, as will be evident from the drawings. The main driving-shaft A' is also furnished with a driving-pulley, A^4 , to which power is applied from any suitable motor.

Resting upon and driven by the four rollers A^2 is a large cylinder, B. This cylinder is peculiarly constructed, its central portion being formed of two annular flanges, b , placed a short distance apart and covered with wire-netting, as represented at b' in Figs. 4 and 1. The flanged plates b are connected and held rigidly in place by bolts c , and at or near their peripheries are provided with a series of buckets, c' , somewhat like the usual elevator-buckets, the purpose of which will be presently explained. Upon each side of the flanged plates b the cylinder is formed of broad rings

b^2 , bolted to the flanges and having small inward flanges b^3 upon their outer sides, their ends being closed by wood or metal plates C, 55 supported on the main frame in any suitable way. The inner surfaces of the rings b^2 are chilled, and form hard faces upon which the ore is crushed.

At each end of the cylinder B is hinged to 60 the main frame an arm, D, upon the upper end of which is journaled a shaft, D', extending through the cylinder and carrying within the same two chilled rolls, D², which lie in close relation to the chilled surfaces of the 65 cylinder-rings and serve as crushing-rolls, as will be presently explained. The shaft D' is driven by a gear, d, thereon at each end, meshing with similar gears, c', upon the main driving-shaft, and the upper ends of the hinged 70 arms D rest upon the set-screws d', by which the shaft and its rolls are adjusted to run at any suitable distance from the chilled face of the cylinder, and thereby regulate the extent to which the ore is pulverized. A second 75 shaft, E, passes through the cylinder just in rear of the one just described, carrying rolls E', journaled in the ends of jointed arms E², projecting from the arms D, and also adjusted to and from the cylinder by adjusting-screws 80 e, as clearly seen in Figs. 2, 3, and 6.

The bearing of each of the shafts D' E is provided upon each end with an arm, F, upon which is an adjustable weight, f, for regulating the pressure of the rolls upon the ore. 85

Journaled in the main frame, in rear of the crushing-rolls, is a shaft, G, upon which is secured a right and left hand conveyer-screw, G', which conveys the crushed material from each end of the cylinder to the central screen. 90 This shaft is at one end provided with a pulley, g, connected by a belt, g', with a similar pulley, g², upon the shaft A³.

The ore is passed into the cylinder through a hopper, H, at each end, (shown in Fig. 4,) 95 and an inclined board, H', is secured in the cylinder B, as in Figs. 4 and 5, having laterally-inclined extensions H², which direct the ore therefrom back to the crushing-rolls upon each side of the machine.

Below the center of the machine, under the cylindrical screen, is a spout, I, through which the crushed material which passes through said screen is carried away. This spout has

its upper edges secured to large circular partitions or rings which run in annular grooves *i*, formed in the edges of the flanges *b*, and prevents the escape of dust, making a dust-tight joint without excessive friction of the parts, as will be seen at once.

The whole machine is inclosed by a casing, *K*, and the dust is confined therein.

In operation the ore is fed into the machine at each end through the hoppers *H* and falls in front of the crushing-rolls *D*. These rolls are constantly revolving, as is also the main cylinder *B*, and the ore passing between the chilled inner face of this cylinder and the rolls is crushed. The other rolls, *E*, finish the crushing, and the material is then carried from each side to the central screen by the right and left hand conveyer *G*. Such portion of the ore as is properly crushed passes through the meshes of this screen and off through the spout *I*, while the larger particles are caught by the elevator-buckets within the screening-chamber and carried up to the top of the cylinder, where they drop upon the incline *H'*, and are by this and its lateral extensions directed to each side of the machine in front of the crushing-rolls, under which they are again passed and the crushing completed. The rolls are adjusted readily by means of thin screws *d*, to regulate the size to which the ore is reduced, and the amount of power governed by moving the weights *f* to and fro upon the arms *F*.

The cylinder *B* being provided with small inwardly-projecting flanges upon its ends, the ore is kept from contacting with and wearing the stationary end boards, *C*, and the cylinder itself is held steady and prevented from slipping endwise upon its supporting and driving rollers by annular shoulders *m*, formed upon the cylinder, as in Fig. 4.

It is evident that a machine of smaller capacity, but embodying the same principles of construction and operation, could be used by omitting one end of the cylinder and its accompanying parts, and simply using one end with its crushing-rolls and the flanged or enlarged screen-chamber.

The whole machine being cased in, the dust is confined within the casing and cannot escape. The only material break in this casing is where the spout *I* passes through it, and this spout being fitted in the grooved edges of the screening enlargement, the dust is not allowed to escape even at this point. This is also the point at which the dust rises in the greatest volume, because of the finely-crushed material falling over and upon the meshes of the wire, as will be seen at once.

Having thus fully described my invention, what I claim as new, and desire to secure by Letters Patent, is—

1. In an ore-crusher, the combination of a main frame, four rollers journaled therein and connected by driving-belts, a rolling cylinder supported upon and driven by said

rollers, an annular screening-chamber forming the central portion of said cylinder, crushing-rolls located in each end thereof and geared together, and means for feeding the crushed ore from the ends of the cylinder to its central screen, substantially as and for the purpose set forth.

2. In an ore-pulverizer, the combination of the main frame, a rolling crushing-cylinder, crushing-rolls therein, shafts, journal-boxes, arms hinged upon the main frame, and weighted arms connected with said journals, whereby the rolls are pressed upon the inner surface of the cylinder, substantially as and for the purpose set forth.

3. In an ore-crusher, the main frame and a rolling cylinder within which the ore is crushed, in combination with a pair of crushing-rolls, journal-boxes, arms hinged on the main frame, a second pair of rolls, journal-boxes therefor, jointed arms connecting the two pairs of journal-boxes, and weighted arms secured to the journal-boxes of each roll to press them down upon the inner surface of the cylinder, substantially as and for the purpose set forth.

4. In an ore-crusher, the combination of a main frame, a casing, a rolling crushing-cylinder formed with annular grooves, and a spout having its upper edges running in said grooves, whereby the dust is prevented from escaping from the machine, substantially as and for the purpose set forth.

5. In an ore-crusher, a rolling cylinder provided with a central enlargement covered by wire-netting, and a pair of crushing-rolls located within the cylinder, in combination with a right and left hand conveyer located in rear of the crushing-rolls and adapted to carry the crushed material from the ends of the cylinder to the central screen, substantially as shown and described.

6. In an ore-crusher, the combination of the rolling cylinder *B*, the crushing-rolls *D*, the arms *D*, hinged upon the main frame, the weighted arms *F*, secured to the journals of said crushing-rolls, and the set-screws *d*, all constructed and arranged to operate substantially as and for the purpose set forth.

7. In an ore-crusher, the combination of a rolling cylinder having a central enlargement covered with wire-netting, ledges or buckets within said enlargement, crushing-rolls working against the inner surface of the cylinder, a right and left hand conveyer for carrying the crushed ore to the screening-chamber, and an incline to receive the crushed ore carried up by the buckets and return it to the crushing-rolls, substantially as and for the purpose set forth.

In testimony whereof I affix my signature in presence of two witnesses.

CHARLES KAESTNER.
